METAL SHEET DRYING OVEN

Frederick S. Bailey, Morristown, N. J., assignor
to National-Standard Company, a corporation
of Michigan

Application December 14, 1948, Serial No. 65,209

4 Claims. (Cl. 34—150)

1

This invention relates to drying apparatus for coated or lithographed metallic plates and plates of other material and has for one of its objects the provision of means by which a flow of air at relatively high velocity is directed around the plates while the same are being transported through a drying oven, to effectively dry the plates.

In machines of the character to which the present invention relates, the plates which are lithographed or have their faces otherwise coated or varnished, are supported in spaced relation and on edge upon chain or other conveyors and are moved through a relatively lengthy oven or chamber in which heated air is circulated, the heated air passing around the plates and over the coated surfaces of the plates to dry the same. In machines of this character it is desirable that the air flow which is circulated around the plates be of relatively high velocity to expedite the drying and it has been found that when an effort is made to direct the air at high velocity between and around the plates by known means, and while the plates are being supported on edge and arranged in a plane perpendicular to the direction of movement of the conveyor, there is a tendency for adjacent plates to move towards one another due to the reduction in air pressure between the plates. This has resulted in a flutter or chattering movement of the plates, sometimes bringing the coated side of one plate into contact with an adjacent plate and causing defacement or marring of the coating.

The present invention therefore has reference to means by which air flow under considerable velocity can be directed around the plates to greatly expedite the speedy and uniform drying of the same and without causing the undesirable fluttering action of the plates. More particularly, the invention contemplates the provision of a plurality of air nozzles arranged with their outlets facing an edge of the plates carried on the conveyor and across the nozzles, the nozzles being preferably provided with slot-like outlets disposed at an angle with respect to the edges of the plates that are moved past said nozzles.

The invention further contemplates the provision of means for circulating the heated air and directing the same to and through the angularly-arranged nozzles, and in other features to be hereinafter pointed out and designated in the claims.

In the accompanying drawings, wherein an illustrative embodiment of the invention is disclosed, Fig. 1 is a side elevation, with parts broken

away, and other parts in section, of the entrance end of a drying oven constructed in accordance with the invention; Fig. 2 is a sectional view taken on the line 2—2 of Fig. 1, looking in the direction of the arrows; Fig. 3 is a vertical sectional view through the oven; Fig. 4 is an enlarged top plan view of a portion of two of the air nozzles; Fig. 5 is a sectional view taken on the line 5—5 of Fig. 4, looking in the direction of the arrows; Fig. 6 is a top plan view of the bank of nozzles; Fig. 7 is a horizontal sectional view through the duct in which the heated air is forced to the nozzles, the section being taken on the line 7—7 of Fig. 1, looking in the direction of the arrows; Fig. 8 is a top plan view of a group of nozzles of modified construction, and Fig. 9 is a top plan view of a plurality of nozzles of another type.

Referring to the embodiment of the invention disclosed in Figs. 1 to 7 of the drawings, 1 indicates the body or casing of the drying oven, which is generally of known construction, and consists of an outer covering 2, which may be of sheet metal, and an inner lining 3 of a suitable heat-resisting or insulating material. The body or casing of the oven is open and hooded at the forward or front end 4 and is also open at its rear end, not shown. At the forward end 4, the coated or lithographed plates 5 are fed to a conveyor to be carried through the oven to the rear end of the same and at that point the plates will have been dried and are either manually or mechanically removed from the conveyor.

In the embodiment of the invention shown, the conveyor consists of a pair of chains 6 and 7 extending around suitably driven sprockets, two of which are shown at 8 and 9. Plate carriers in the form of wire racks 10 are carried by the chains, and the plates 5 are supported on edge on the upper stretches of the conveyor by the racks 10 and are thus carried through the oven. The structure above described is well known in this art and is herein briefly described in order to indicate its association with the novel features of the present invention.

Heated air is circulated within the chamber defined by the casing 1, said air being drawn in at the front or forward end 4 of the casing 1 and heated by a heater 11 mounted on top of the casing 1 from whence the heated air is drawn by the circulating blower 12 which forces the heated air down through a duct 13 and into a chamber or manifold 14 which directs the air flow through slot-like nozzles 24 and up around the plates 5 in a manner to be presently described.

The circulating blower 12 is operated by an electric motor 15 which drives the shaft 16 of the blower by means of the chain drive 17.

At the top of the casing 1 near the forward end of the same is shown exhausting means by which fumes and gases are exhausted out of the oven. Such exhaust means includes an exhaust fan 18 operative to draw the fumes and gases upward through the duct 19 and out through the hooded exhaust pipe 20. The exhaust fan 18 is driven by the electric motor 21 through suitable chain drive 22. A grid 23 is located above the conveyor below the air-circulating and exhaust means just described.

The duct 13, leading from the air-circulating blower 12, extends downwardly from the outlet of the blower 12 on the outside of the casing 1 to a chamber 14 which is herein termed a "manifold" since it serves to divert the heated air under considerable velocity through a plurality of slot-like nozzles 24 from whence the air is expelled to be forced around the plates 5 carried by the conveyor above these nozzles, in the manner indicated by the arrows 40, 41 and 42 in Fig. 3. The manifold or chamber 14 is of the shape most clearly seen in Fig. 1 wherein it will be noted that it is of largest capacity at its center and is tapered at its opposite ends as indicated at 25 and 26. In its interior the chamber or manifold 14 is provided with a plurality of curved, vertically-arranged partitions or baffles 27 tending to direct the air streams throughout the chamber 14, distribute the same to, and secure uniform air flow through the substantial number of outlet nozzles 24, located at the top of the chamber or manifold 14.

To provide the nozzles, the top wall 27' of the chamber or manifold 14 is formed with a plurality of spaced slots 28 forming outlet openings, and the nozzles 24 are arranged over these slots 28 and form upward continuations of the same as will be noted in Fig. 5. Each nozzle is composed of two angular plates or pieces, indicated respectively at 29 and 30. The piece or plate shown at 29 includes a base flange 31 attached by the screws 32 to the top wall 27' of the chamber or manifold 14. Said piece or section 29 is provided with an upwardly-extending vertical flange 33 which is at a slight angle to perpendicular and is provided with a laterally extending or horizontal flange 34 at the top. The nozzle piece or plate indicated at 30 has a base flange 35, secured by the screws 36 to the top wall 27' of the manifold 14, and also has a vertical flange 37 extending upwardly and at a greater angle from vertical than the vertical flange 33. At the top, the flange 37 is provided with the horizontal flange 38. The two flanges 34 and 38 are embraced by suitable clips 38a provided at spaced intervals along the slot-like apertures or mouths of the nozzles thus formed, so that these outlet ends of the nozzles are reinforced and held against enlargement or distortion. It will be noted that the arrangement just described is such as to result in slot-like apertures which are smaller at their outlet ends than at their entrance ends, the latter ends being defined by the slots 28 in the top wall 27' of the casing 1. The slot-like nozzles are closed at their opposite or side ends by the vertical wall plates 39.

Attention is directed to the fact that the nozzles 24 are so arranged that their slot-like outlet openings are disposed angularly to the plane of the plates 5 carried by the conveyor above them, as will be more clearly noted in Fig. 6,

wherein the plates 5 are indicated in dot-and-dash lines, and the same extend at substantially right angles to the side walls of the casing while the slot-like outlet ends of the nozzles cross the lower edges of these plates at an angle. With this arrangement it will be apparent that an unequal air velocity will be caused between the plates. This will be noted in Fig. 3, wherein the arrows indicated at 40 show maximum air velocity in the areas around the central portions of the plates while air flow toward the ends of the plates, as indicated at 41 and 42 is considerably less. As a result the total resultant forces which tend to draw two adjacent plates together when a uniform air velocity or flow is created between them, will be considerably reduced and higher air velocities can be maintained without causing the plates to flutter and be possibly brought into contact with one another to mar or deface the coatings thereon.

In the embodiment of the invention shown in Figs. 1 to 7 inclusive, the nozzles are shown as being provided with slot openings which extend continuously, and without change in angularity from one end of the nozzle to its opposite end. In the embodiment shown in Fig. 8, a slightly different arrangement is shown wherein the outlets 50 are of flattened V-formation. In the arrangement shown in Fig. 9 the nozzles are divided into two groups, namely those shown at 51 and those indicated at 52. The nozzles in the two groups are staggered or alternated, but those in each group are disposed at an angle to the plates which are carried above them and hence the variations in air velocity exists in this structure in the manner explained with respect to the structure of Figs. 1 to 7.

In the operation of the drying oven, the plates are loaded on the conveyor at the forward end 40 of the oven and are carried thereby through the oven and above the nozzles 24 to receive the blasts of heated air therefrom under relatively high velocity. Due to the unequal force of the air blasts between the plates because of the angularity of the nozzle outlets with respect to the plates carried above them, flutter of the plate will not take place but drying of the plates will be speeded up. After the plates are carried beyond the inner end of the bank of nozzles 50 they proceed through the chamber or oven in known manner toward the outlet end where they are either manually or mechanically removed from the conveyor. Throughout the casing 1, and beyond the nozzle bank, heating elements 55, fans 56, and other known elements are generally employed for providing required air temperature and circulation within the oven chamber as is known in this art.

Having described one embodiment of the invention, it is obvious that the same is not to be restricted thereto, but is broad enough to cover all structures coming within the scope of the annexed claims.

What I claim is:

1. In a drying apparatus, a drying chamber, means for transporting a plurality of plates on edge and in spaced relation through said drying chamber, an air chamber located below the plates and over which the plates are moved by said transporting means, said air chamber having a plurality of apertures in its top wall extending across the air chamber for a distance nearly equal to the width of the plates, said apertures being in the form of nozzles with elongated slot-like outlets, said slot-like outlets be-

ing arranged in parallelism and all being disposed with their longitudinal axes transverse to the path of travel of the plates, said slots all being at an acute angle in respect to the plane of the plates carried past and above them so that an unequal air velocity will be created between adjacent plates and flutter of said plates will be minimized.

2. In a drying apparatus, a drying chamber, means for transporting a plurality of plates on edge and in spaced relation through the drying chamber, an air chamber located below the plates and over which the plates are moved by said transporting means, said air chamber having a plurality of apertures in its top wall in the form of nozzles with elongated slot-like outlets, some of said nozzles being in staggered relation to others, said slot-like outlets being arranged in parallelism and all being disposed with their longitudinal axes transverse to the path of travel of the plates, said slots all being at an acute angle in respect to the plane of the plates carried past and above them so that an unequal air velocity will be created between adjacent plates and flutter of said plates will be minimized.

3. In a drying apparatus, a drying chamber, means for transporting a plurality of plates on edge and in spaced relation through the drying chamber, an air chamber located below the plates and over which the plates are moved by said transporting means, said air chamber having a plurality of apertures in its top wall in the form of nozzles with elongated slot-like outlets, said nozzles being all of flattened V-formation and being arranged in parallelism and all being disposed with their longitudinal axes transverse to the path of travel of the plates, said slots being at an acute angle in respect to the plane of the plates carried past and above them so that

an unequal air velocity will be created between adjacent plates and flutter of said plates will be minimized.

4. In a drying apparatus, a drying chamber in which plates are carried while being supported on edge and disposed in spaced relation and substantially parallel, an air chamber located below the plates, said air chamber having a plurality of elongated slot-like spaced openings in its top, a nozzle arranged over each slot-like opening, each nozzle having a slot-like outlet defined by opposed vertical walls, one of said walls being substantially perpendicular and the other being at an angle to vertical whereby the slot-like outlet end of the nozzle is smaller than the slot-like opening in the air chamber over which the nozzle is positioned, the slot-like outlets of the nozzles being arranged in parallelism and all being disposed with their longitudinal axes transverse to the path of travel of the plates, said slot-like outlets all being at an acute angle in respect to the plane of the plates carried past and above them.
